DISPLAY DEVICE

Nicholas Sandor and Felix Edward Laszlo
 Sandor, Surbiton, Surrey, England, assignors
 to I. S. M. Limited, London, England, a British
 company

Application July 12, 1938, Serial No. 218,816
 In Great Britain July 13, 1937

4 Claims. (Cl. 40—37)

This invention relates to advertising, indicating and displaying devices and is applicable both to the display of large advertisements such as those usually seen on bill boards and to the display of small advertising panels or frames of a size usual in display cabinets. More particularly the invention relates to such devices in which a plurality of frames or the like containing the matter to be displayed are disposed in a cabinet having a display window and are adapted to be brought into view successively behind the display window. The invention has for its object to provide an improved construction of mechanism for displacing the frames.

In accordance with the invention there is associated with each of the frames one or more fluid operated pistons or plungers movable in cylinders and adapted to raise the frames containing the matter to be displayed successively into position opposite the display window, the supply and exhaust of fluid to the cylinder or cylinders being controlled mechanically, for example, by means of rotating cams or the like acting in succession on the valves controlling the admission or exhaust of the working fluid to the cylinder, the cams being mounted on a shaft driven from any convenient source of power. Suitably compressed air is employed as the operating medium. The compressed air may be stored in a container and the pressure maintained by an electric motor and compressor, the motor also serving through reduction gearing to drive the mechanical means controlling the admission and exhaust of the compressed air to the cylinders.

In one convenient arrangement in accordance with the present invention the frames or the like containing the matter to be displayed are arranged at the bottom of a cabinet beneath the level of the viewing window. To each frame is attached two wires or the like passing over pulleys disposed at the upper end of the cabinet and supporting at their other ends counterweights slightly heavier than the weight of the frame to be raised, one of each pair of the counterweights being in the form of a piston working in a cylinder under the control of compressed air. The counterweight in the form of a piston, is so arranged in its cylinder that when the frame is not in viewing position i. e. is disposed below the level of the viewing window the piston is at the end of its stroke under pressure.

A common container for the supply of compressed air to all the cylinders is provided, a conduit leading from this container to a common valve block. The valve block contains a plu-

rality of valves, one for each cylinder, the valves being normally pressed by springs against their seatings within the valve block to place the cylinders into communication with the compressed air container. The valves are adapted to be operated by means of cams to allow air to exhaust from the corresponding cylinders.

When it is desired to raise any particular frame the valve controlling the exhaust of air from that cylinder is opened and the counterweight, being heavier than the frame, thus descends in its cylinder raising the frame connected therewith behind the viewing window. After a predetermined interval of time the air is again admitted to the cylinder, thus raising the counterweight and lowering the frame.

As the arrangement is to operate continuously with the frames being raised in succession, the valves controlling the admission and exhaust of air to each cylinder from the common chamber are operated by means of cams or the like, while the motor may drive the compressor continuously, a suitable safety control may be provided to prevent the pressure from building up beyond a predetermined limit. The cam shaft may be rotated at any suitable speed through reduction gearing from the electric motor driving the compressor.

The number of frames and the time interval during which each frame is to be displayed behind the window is dependent on the speed of rotation of the cam shaft and the shape and setting of the cams, which are preferably keyed on their shaft so that their setting can be varied.

The device forming the subject of the present invention may conveniently be combined with an advertising device as shown and described in our prior United States Patent No. 2,132,085.

In such an arrangement certain of the cards which may consist of indicia at two levels are arranged to be brought successively into a position behind the viewing window, while such successive display of the cards can be temporarily interrupted to permit of other cards being displayed behind the viewing window at the will of the operator.

In such an arrangement a common container for the supply of compressed air to all of the cylinders is provided, conduits leading from an interposed valve block to the various cylinders. In the valve block between the air supply and the conduits leading to the various cylinders there are interposed valves which are normally pressed by a spring against their seatings, preventing the exhaust of compressed air from the various cylinders.

ders, the valves being adapted to be depressed by means of the cams on the rotating shaft or, by a lever operated by a button or key, to allow air to exhaust from the corresponding cylinder or cylinders.

On operation of the valve, communication between the corresponding cylinder and the common compressed air chamber is interrupted and the compressed air exhausted to atmosphere thus allowing the piston to descend and raising the associated panel or frame containing the advertising matter behind the viewing window.

The cam shaft is preferably mounted in such manner that it is normally held by means of electro-magnets or relays or the like in such position that the cams operate the valves controlling the supply and exhaust of compressed air to the cylinders. Depression of certain of the keys, however, serves to cut off the current to the magnets or relays or the like, thus allowing the cam shaft to assume a floating position which serves to stop the elevation of those frames normally displaced in sequence behind the window and allowing the frame corresponding to the key which is depressed to be raised.

Two embodiments of the invention are illustrated somewhat diagrammatically in the accompanying drawings in which Fig. 1 is a front elevation of the apparatus and Fig. 2 a section on the line II—II of Fig. 1. Fig. 3 is a plan of Fig. 2. Fig. 4 is a detail to enlarged scale showing valves operated by the cam shaft which is driven through reduction gearing, while Fig. 5 is a section on the line IV—IV of Fig. 4. Fig. 6 is a front elevation of a modification in which the frames or panels may be operated either by cams or by push buttons, while Fig. 7 is a side elevation of the embodiment shown in Fig. 6.

Referring now to the embodiment illustrated in Figs. 1 to 5 of the accompanying drawings, 1 denotes the base of the advertising or like apparatus, 2 are uprights and 3 an upper cross-member of the cabinet of the apparatus. A plurality of vertical guide members 4 are provided one for each frame or panel to be displayed, the vertical guide members 4 being embraced by the grooved members 5 mounted at the corners of the frames or panels 6 to be raised into position in register with a viewing window of the cabinet not shown.

Each frame or panel 6 is supported by a pair of wires, chains or the like, 7, 7a, passing over pulleys 8, on shafts 9, supported at each side of the cabinet on the cross-member 3. Each of the chains 7 is connected at the other end with a piston or the like 10 in the form of a counterweight movable in a cylinder 11. Since the counterweights at one side of the cabinet will follow the movement of the corresponding counterweights at the other, pistons are not required at each side of the cabinet. Thus the chains 7a are provided with counterweights 10a but these counterweights need not move in cylinders.

Each cylinder 11 is connected to a common valve block 12 by a connecting pipe 13 compressed air being supplied to the cylinders 11 through the valve block 12 from a container or reservoir 14 through a suitable delivery pipe 15. The air compressor 16 supplying the container 14 is driven from an electric motor 17, the motor also serving to drive, through belts 18, 19 and pulleys 20, 21, 22, 23, reduction gearing (not shown) but enclosed in the casing 24, the cams 26 mounted on spindle 25 operating the valves

controlling the admission and exhaust of compressed air to the cylinders 11.

The valve block 12 contains a plurality of two-way valve members 27, one for each cylinder 11, each valve being adapted to seat itself either on the seating 28, as shown, to put the cylinder into communication with the common compressed air container 14, or on the seating 29 to permit air from the cylinders 11 to exhaust through the pipe 13 and ports 30. The valves are controlled by springs 31, 32 and are operated through the push members 33 in a sequence determined by the setting of the cams 26 on the shaft 25.

In operation, the valve spindle 25 is rotated slowly, being driven from the electric motor 17, the cams 26 acting, in predetermined sequence depending on the setting of the cams 26, on the push members 33 each of which places the corresponding cylinder 11 in communication with the atmosphere through the pipe 13 and port 30 thus allowing the air to exhaust whereupon the counterweight, being heavier than the frame or panel, winds the chains or the like 7, 7a over the pulleys 8 and raises the panel or frame containing the advertising matter (not shown) into positions in register with the viewing window. When the advertisement has been displayed for a convenient length of time another valve is operated by its cam to exhaust the air for another cylinder which may be the adjacent cylinder whereby the next frame or panel is raised in front of the frame displayed behind the viewing window. The frame formerly raised then being lowered behind the frame now displayed behind the viewing window.

A suitable advertisement is mounted at the rear of the cabinet on a level with the viewing window so that when all of the frames are in the lowermost position i. e. when the apparatus is not in operation, such advertisement is always displayed.

Apparatus in which the panels may be operated either by cams or by push buttons is illustrated in Figs. 6 and 7 of the accompanying drawings in which the same reference characters are used to denote corresponding parts, it being understood that the panels or frames will normally be displayed in succession behind the observation window, while a person can by depressing a button suspend such successive display and select any desired panel to be displayed.

In the arrangement illustrated in Figs. 6 and 7 the cam shaft 25 is driven from a spindle 34 through bevel gearing 35 and a chain drive 36. The cam shaft 25 is mounted in brackets 37 disposed one at each side of the framework, the brackets 37 being adapted to be moved by means of electro-magnets 38. The electro-magnets 38 are normally energized and serve to hold the brackets 37 in such position that the cams 26 on the shaft 25 supported thereby, actuate pusher rods 33 operating valves similar to those shown in Fig. 3 of our said U. S. Patent 2,132,085 to place the cylinders 11 successively in communication with the atmosphere whereby the corresponding frame is raised into viewing position.

Across the front of the machine there is disposed a key board 39 containing a plurality of press-buttons or keys one of which is shown at 40. Such keys are connected in circuit with the electro-magnets 38 say by the shoulders 42 on the keys closing a contact on the back of the key board 39 and serve when depressed to break the electrical circuit, thus allowing the brackets 37 to move away from the electro-magnets and the

cam shaft 25 to assume a floating position in which in lieu of actuating the rods 33 the cams merely raise and lower the shaft. When the electro-magnets are de-energized by the depression 5 of one of the keys 40 the display of panels or frames containing the matter to be displayed in succession is interrupted. The depression of the key 40 serves to operate a bell-crank lever 41 to which is attached a pusher arm 33a serving to 10 operate the corresponding valve in the valve block 12 thus exhausting the corresponding cylinder and permitting the frame or panel corresponding to the depressed key 40 to be raised into viewing position in register with the observation window.

15 We claim:—

1. A display device comprising a cabinet, an observation window in said cabinet, a plurality of frames, said frames containing matter to be displayed and being disposed rearwardly of said observation window and movable in said cabinet, a plurality of fluid motors associated with said frames for moving said frames in said cabinet, said motors each including at least one counter-weight connected for movement in opposition to 20 the frame and movable by fluid under pressure in a piston against the action of gravity, a plurality of valves for controlling the supply and exhaust of fluid to and from said fluid motors and means for operating said valves in predetermined succession to move said cards behind said observation window.

2. A display device comprising a cabinet, an observation window in said cabinet, a plurality of frames, said frames containing matter to be displayed and being disposed rearwardly of said observation window and movable in said cabinet, a plurality of fluid motors, one for each of said frames for moving said frames into and out of viewing position, each of said fluid motors comprising a cylinder and a piston in the form of a counterweight movable by pressure fluid, in said cylinder in opposition to the frame against the action of gravity, each of said pistons being operatively connected to one of said frames, valves for 35 controlling the admission and exhaust of working fluid to said cylinder and means for operating

said valves in predetermined succession to permit movement of said frames behind said observation window.

3. A display device comprising a cabinet and observation window in said cabinet, a plurality of frames, said frames containing matter to be displayed and being disposed laterally of said observation window and movable in said cabinet, a plurality of fluid motors associated with said frames for moving said frames in said cabinet, a plurality of valves for controlling the admission and exhaust of working fluid to said fluid motors, mechanically operating means for operating said valves in predetermined succession to permit movement of said frames behind said observation 15 window, other means for independently operating at least some of said valves, said means comprising a plurality of keys and means operable on depression of a key to operate an associated valve and means operable on depression of some 20 at least of said keys to interrupt the operation of the mechanically operating means whereby the successive display of frames may be interrupted and the frames displayed at the will of an operator.

4. A display device comprising a cabinet and observation window in said cabinet, a plurality of frames, said frames containing matter to be displayed and being disposed laterally of said observation window and movable in said cabinet, a plurality of fluid motors associated with said frames for moving said frames in said cabinet, a plurality of valves for controlling the admission and exhaust of working fluid to said fluid motors, a cam shaft, a plurality of cams on such shaft for 30 operating said valves in predetermined succession to permit movement of said cards behind said observation window, means for holding said cam shaft in operative position, a plurality of keys, said keys on depression serving to operate said 35 fluid motors and release said holding means to interrupt said successive display of frames and to permit of frames being displayed at the will of the operator.

NICHOLAS SANDOR.

FELIX EDWARD LASZLO SANDOR.
